(Cl. D80—5)

To all whom it may concern:

Be it known that I, Murray A. Kaufman, a citizen of the United States, residing in New York, county of New York, State of New York, have invented a new, original, and ornamental Design for a Combined Display Container and Decorative Vase or Similar Article, of which the following is a specification, reference being had to the accompanying drawing, forming a part thereof.

Fig. 1 is a side elevational view of a combined display container and decorative vase or similar article showing my new design;

Fig. 2 is a side elevational view thereof showing the parts in separated position; and

Fig. 3 is a top plan view thereof.

I claim:

The ornamental design for a combined display container and decorative vase or similar article, substantially as shown.

MURRAY A. KAUFMAN.
